UNITED STATES PATENT OFFICE.

PHILIP LOEWE, OF CHICAGO, ILLINOIS.

TRUNK.

SPECIFICATION forming part of Letters Patent No. 300,378, dated June 17, 1884.

Application filed April 2, 1884. (No model.)

To all whom it may concern:

Be it known that I, PHILIP LOEWE, a citizen of the United States, residing at Chicago, in the county of Cook and State of Illinois, 5 have invented certain new and useful Improvements in Trunks; and I hereby declare the following to be a full, clear, and exact description of the same.

As it is desirable in trunks to render every 10 portion of the interior available, it is common to form receptacles in the lid. As commonly constructed, the lid opens backward to an angle a little beyond the perpendicular, rendering the receptacles therein somewhat 15 difficult of access from the front side of the trunk, and limiting them to certain forms and purposes. With a view to overcoming this difficulty in a measure, the lids have heretofore been divided longitudinally into two 20 parts, each being hinged to a side of the trunk. This construction lightens the strain upon the hinges, and thus permits the parts to be brought more nearly to a horizontal position when open than where the undivided 25 lid is employed. It does not, however, meet all the requirements, since it is obvious that one of them has to be reached by leaning over both the trunk and the other one in cases 30 where the trunk stands near the wall, as it usually does, and that they render the interior of the trunk itself somewhat difficult of access.

My invention consists in dividing the lid transversely into two parts, providing one 35 with a "valance" to overlap the other, and hinging each part to an end of the trunk, whereby the parts may be turned out to a horizontal position, rendering them easy of 40 access themselves and available for all purposes without presenting any obstacle at the side of the trunk.

In the drawings, Figure 1 is a perspective view of a trunk provided with my improvements; Fig. 2, a perspective view of the interior of the hinge, and Fig. 3 a perspective view in detail of a suitable fastening device.

A is the body of the trunk, and B B' the two halves of the lid formed by dividing the trunk transversely at its center. Each is 45 hinged to an end of the body, and is provided

with one or more suitable receptacles, C. If desired, the meeting ends of the parts B and B' may be beveled in contrary directions, although the construction shown in the drawings with a straight joint will answer the 55 purpose.

D is the hinge which I prefer to use. As commonly constructed, hinges of this character are adapted to permit the lid to be turned up to an angle a little beyond the perpendicular, the curved arm *t* being firmly secured to one half of the hinge, and sliding within a guide formed in the other half, the part which slides in the guide being provided with a stop to retain it therein. For my lid, however, it is desirable that the hinge be adapted to permit the halves of the lid to be turned over nearly or quite to a horizontal position, and for this purpose I form a guide, *s*, in each half of the hinge, and provide each end of the curved arm with a stop, *r*, to prevent it from slipping out of the guide, making it nearly or quite double the length of the arm employed in ordinary hinges, and correspondingly enlarging the sweep. Instead of being 60 secured to one-half of the hinge and sliding within a guide in the other, it slides within corresponding guides in both halves of the hinge, thus permitting the hinge to be opened to the extent requisite for my purpose. Each 65 half of the lid is provided on its side edges with plates *q*, secured thereto, which, when the lid is closed, enter the top of the body A, forming stays to prevent lateral wrenching. The part B' is provided at the end where it 70 meets the part B with a valance, which overlaps the latter when the parts are closed.

A suitable securing device is shown in Fig. 3, and consists of a hasp-lock formed in two parts, E and E', one of which is pivoted to 75 the top of the part B, and the other to the top of the part B'. Each part is provided with a socket, *p*, upon one side, and a pin or projection, *o*, upon the other, whereby, when the parts are brought together, they interlock. 80 The part E is provided with a spring-hasp, *n*, and the part E' with a staple, *m*, to pass through the slot in the hasp and receive a padlock. Any other suitable form of construction may be employed as to the hinges 85 90 95 100

and fastening device, although those described are well adapted to the purpose.

What I claim as new, and desire to secure by Letters Patent, is—

5. In combination with the body of a trunk, a lid formed in two parts by transverse division, with an overlapping portion on one part, said parts being hinged to the ends of

the trunk, and provided with means, substantially as described, for securing them when closed.

PHILIP LOEWE.

In presence of—

THOMAS A. BANNING,
E. F. HUBBARD.
